Primary Examiner—Paula A Greene(74) *Attorney, Agent, or Firm*—Waddey & Patterson; Dennis H. Nunez(57) **CLAIM**

What is claimed is the ornamental design for a handle for a toilet seat lifter, as shown and described.

DESCRIPTION

FIG. 1 is a top view showing the handle for a toilet seat lifter of applicant's invention.

FIG. 2 is a front view of the handle for a toilet seat lifter of applicant's invention.

FIG. 3 is a side view of the handle for a toilet seat lifter of applicant's invention.

FIG. 4 is a back view of the handle for a toilet seat lifter, the undisclosed portion is not part of the claimed design;

FIG. 5 is another top view of the handle for a toilet seat lifter of applicant's invention; and,

FIG. 6 is a perspective view of the handle for a toilet seat lifter on the unclaimed environment of the closed toilet seat.

The broken lines showing of the words "Logo Here" and environment are included for the purpose of illustration and form no part of the claimed design.
